GUIDES ON CARBON PAPER

George Shenker, Brooklyn, N. Y.

Application January 6, 1955, Serial No. 480,245

1 Claim. (Cl. 282—28)

This invention relates to new and useful improvements in carbon paper for making carbon copies.

More particularly, the present invention proposes the construction of an improved carbon paper guide which will permit the user to tell quickly and conveniently when the carbon paper is correctly in place and which will permit pages of approximate fixed numbers of words to be easily and mechanically produced with uniform margin and symmetry.

As a further object, the present invention proposes forming the carbon paper guide of a sheet of carbon paper marked, perforated or cut with vertical and horizontal indications to show the user where to begin and where to end a 300-word page with a one inch margin or a 250-word page with a one and one-half inch margin.

Still further, the present invention proposes constructing the carbon paper guide with the vertical and horizontal indications located in diagonally opposed corner portions in sets so that the life of the carbon paper sheet may be extended by turning the sheet around.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a front perspective view of a carbon paper sheet constructed and arranged in accordance with the present invention, when the carbon paper is of the exact size of the writing paper.

Fig. 2 is a rear perspective view of the sheet shown in Fig. 1.

Fig. 3 is a sectional view taken on line 3—3 of Fig. 1.

Fig. 4 is a sectional view taken on line 4—4 of Fig. 1.

Fig. 5 is a view similar to Fig. 1 but illustrating a modification of the present invention.

Fig. 6 is a fragmentary perspective view of the structure shown in Fig. 5.

Fig. 7 is a view similar to Fig. 5 but showing both sets of additional diagonal guide indications removed.

Fig. 8 is a view similar to Fig. 2 but illustrating another modification of the present invention.

Fig. 9 is a view similar to Fig. 1 but illustrating a still further modification of the present invention.

The carbon paper guide, in accordance with the first form of the invention illustrated in Figs. 1 to 4, inclusive, comprises a sheet of carbon paper 15 of the same size as standard typewriter paper of the type commonly used in typing manuscripts, letters and the like.

Sheet 15 has the usual carbon face 16 and plain back 17 and preferably is of the same thickness as the usual sheet of carbon paper and can be made from the same.

Sheet 15 has like diagonally opposed upper left and lower right corner portions 18 and 19, respectively, and like opposed upper right and lower left corner portions 20 and 21, respectively.

2

Corner portions 18 and 19 have like spaced vertical margin indications 22 and 23 and like spaced horizontal starting and finishing indications 24 and 25. Indications 22 and 24 are formed on the sheet by cutting or otherwise forming cut-out portions on sheet 15, indications 22 and 24 being edge portions of the sheet. The indications 23 and 25 spaced parallel to indications 22 and 24, respectively, are lines formed upon the back 17 of the sheet 15.

10 In the example shown in Figs. 1, 2, 3 and 4, the indications 22 and 24 are formed by cutting a one inch square from the upper left and lower right corners of the sheet 15. The indications 23 and 25 are lines formed by a one and one-half inch square formed preferably before indications 22 and 24 are cut.

Sheet 15, in addition, has in diagonally opposed upper right and lower left corner portions 20 and 21 spaced vertical margin indications 26 and 27 and horizontal starting and finishing indications 28. The indications 26 and 28 are formed by cutting out a corner of the sheet, the indications 26 and a portion of indications 28 being edge portions of the sheet. Indications 27 and a portion of indications 28 are lines drawn on the back of the sheet. In the example shown in the first four figures, the indications 26 and part of indications 28 are formed by cutting a one-half inch by one inch rectangle from the sheet corners and scribing a one-half by one and one-half inch rectangle in the same corners of the sheet. The vertical indications 26 and 27 serve as guides for the vertical margins of typing matter and the indications 28 serve to indicate the starting and finishing points of typing matter on the sheet being typed.

35 The new carbon paper guide in the example shown is based on the standard six lines to the vertical inch on all makes of typewriters and may be used primarily to guide those who transcribe manuscripts for submission to editors. The difference in the cut-out corner portions serves to prevent the carbon paper sheet from being improperly positioned, i. e. for the reverse or carbon side to be transposed. The guide indications assure perfect uniformity and symmetry.

40 Instructions for using the carbon paper guide are as follows: Do not use opaque paper. Adjust sheet with carbon paper in the usual manner. Then adjust the rear and front sheets to the one inch or the one and one-half inch indication. The larger cut-out should be visible in the upper left-hand corner of the sheet to prevent using the wrong side of the carbon paper. If a 300-word page with a one inch margin is desired, use carbon paper cut-out corner edge portions as guides. If a 250-word page with one and one-half inch margin is desired, use the scribed or drawn lines as guides. Writing starts at the intersection of the horizontal and vertical cut-out portions or scribed or drawn lines. The last line of a page is 45 written when the horizontal side of cut-out or scribed or drawn lines shows in the lower right-hand corner. To increase the life of a sheet of carbon paper, one should alternate starting with the upper left and lower right cut-outs or scribed or drawn indications.

50 The modification of the invention illustrated in Figs. 5, 6 and 7 is characterized by a carbon paper guide sheet 30 constructed similarly to sheet 15 and having similar parts given the same reference numerals but primed to distinguish the figures. In Figs. 5 and 6, on sheet 30, however, the alternate sets of vertical margin indications and horizontal starting and finishing indications instead of being drawn or scribed on the sheet, are perforated lines. In the use of sheet 30, therefore, the user may tear the sheet along the perforations to obtain a 250-word page guide. This will form a larger cut-out corner portion with edge guide indications which may be more easily

seen through the paper being typed upon than the drawn or scribed lines.

In Fig. 7, the alternate sets of vertical margin indications and horizontal starting and finishing indications are omitted.

The modification of the invention illustrated in Fig. 8 is characterized by the provision of a carbon paper guide consisting of a sheet of carbon paper 31 with square corners which are clear or translucent and uncarboned. Sheet 31 has the usual carbon backing 32 on all the other parts of the sheet except the corners.

Upper right and lower left corner portions 33 and 34, respectively, have vertical margin indications 35 and horizontal starting and finishing indications 36 which are the carbon edge portions of the clear or translucent corner portions 33 and 34. In the example shown, corner portions 33 and 34 are one inch square.

Upper left and lower right corner portions 37 and 38, respectively, have vertical margin indications 39 and horizontal starting and finishing indications 40 which also are the carbon edge portions of these clear or translucent corner portions. In the example shown, the corner portions 37 and 38 are one-half inch by one inch rectangles.

The modification of the invention illustrated in Fig. 9 is characterized by the provision of a sheet 45 of carbon paper which is longer than the standard sheet of typewriter paper. This carbon paper has clipped upper left and lower right corners 46 and 47, respectively. In addition, scribed, marked or perforated on the back 48 of sheet 45 adjacent the clipped corners 46 and 47 are vertical margin indications or lines 49 and 50 and a like alternate set of indications or lines 51 and 52. Connected with the vertical margin indications or guide lines 49 and 50 are horizontal starting indications or guide lines 53 and 54. An alternate set of horizontal starting indications or guide lines 55 and 56 are connected with the alternate set of vertical margin indications or guide lines 51 and 52.

The upper right-hand corner portion 57 and lower left-

hand corner portion 58 of sheet 45 is marked, scribed or perforated with vertical margin indications or guide lines 59 and 60 and with horizontal finishing indications of guide lines 61.

5 While I have illustrated and described the preferred embodiments of my invention, it is to be understood that I do not limit myself to the precise constructions herein disclosed and that various changes and modifications may be made within the scope of the invention as defined in the appended claim.

Having thus described my invention, what I claim as new, and desire to secure by United States Letters Patent is:

A carbon paper guide for typing carbon copies, comprising a rectangular sheet of carbon paper having side and end edges disposed perpendicular to each other, said sheet having a rectangular cut-out at each of the four corners thereof, each of said cut-outs having a vertical side perpendicular to one end edge of the sheet and a horizontal side perpendicular to the adjacent side edge of the sheet, said vertical side defining a vertical typing margin indication, said horizontal side defining a horizontal typing margin indication, the length of the vertical side being equal to the width of the horizontal typing margin, the length of the horizontal side being equal to the width of the vertical typing margin, the side and end edges of the sheet being straight along the entire perimeter of the sheet between the cut-outs, said sheet having two right-angled perforated lines disposed adjacent to each of said cut-outs for enlarging said cut-out to a predetermined size, the two perforated lines being respectively parallel to the two sides of the adjacent cut-out, said two perforated lines respectively defining other vertical and horizontal typing margin indications.
